(57) CLAIM

The ornamental design for a tent as shown and described.

DESCRIPTION

FIG. 1 is a left, front perspective view of a tent of my new design in a first configuration;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof;

FIG. 7 is a left front perspective view of the tent of FIG. 1 in a second configuration with a canopy extending over the tent of FIGS. 1-6;

FIG. 8 is a front perspective view thereof;

FIG. 9 is a rear perspective view thereof;

FIG. 10 is a left side perspective view thereof;

FIG. 11 is a right side perspective view thereof;

FIG. 12 is a top perspective view thereof;

FIG. 13 is an enlarged view of detail area 13-13 of FIG. 1;

FIG. 14 is an enlarged view of detail area 14-14 of FIG. 2;

FIG. 15 is an enlarged view of detail area 15-15 of FIG. 3;

FIG. 16 is an enlarged view of detail area 16-16 of FIG. 4;

FIG. 17 is an enlarged view of detail area 17-17 of FIG. 5; and,

FIG. 18 is an enlarged view of detail area 18-18 of FIG. 6.

The even dashed lines shown in FIGS. 7-12 represent portions of the tent and form no part of the claimed design. The dash dot dash lines of FIGS. 1-6 and FIGS. 13-18 depict the boundaries of the detail areas and form no part of the claimed design.

1 Claim, 15 Drawing Sheets
